UNITED STATES PATENT OFFICE.

CHARLES T. CAHILL, OF BOSTON, MASSACHUSETTS.

SAFETY SPARK-ARRESTER.

1,289,386.

Specification of Letters Patent. Patented Dec. 31, 1918.

Application filed January 28, 1918. Serial No. 214,094.

To all whom it may concern:

Be it known that I, CHARLES T. CAHILL, a citizen of the United States, and resident of Boston, county of Suffolk, and State of Massachusetts, have invented an Improvement in Safety Spark-Arresters, of which the following description, in connection with the accompanying drawings, is a specification, like letters on the drawings representing like parts.

My present invention is a safety spark arrester, particularly intended for use with wood burning stoves, heaters of the like, wherein danger from fire exists. My invention is especially useful in connection with tents or the like having a readily inflammable roof, through which the stove pipe from a heater leads, particularly where wood is used as fuel. A single burning spark from such a heater will burn through the canvas covering and of course destroy the same. The danger of sparks setting fire to tents is so well recognized that in the United States Government equipment for heaters to be used with tents, it is necessary to fit each chimney from the heater with a spark arrester. Heretofore these spark arresters consisted simply in a wire cage fitted into the top of the open end of the smoke pipe and it was necessary to clamber up on top of the tent and fit the same. As such wire cages were made of comparatively fine mesh wire—necessarily of fine mesh in order to catch and arrest sparks from wood—the wire cages frequently became so clogged as to impede the draft. Therefore each time this difficulty occurred, it was necessary to climb up on top of the tent, remove the spark arrester, climb down, clean and shake the same and then climb back to replace it. The difficulty of clambering up onto the top of a tent is considerable, and was expressly disagreeable in cold or rainy weather. Furthermore, during the time of removal of such prior spark arresters and while being cleaned and before replaced, the danger of fire from sparks was, of course, imminent, and numerous fires have actually occurred during these intervals. My invention obviates the difficulties above noted by providing an economical, quickly and readily adjusted spark arrester within the length of stove pipe inside the tent or other building, where the stove may be erected. Such spark arrester is preferably a short distance

above the stove and within convenient reach. Furthermore, in order to provide a safety factor and enable the removal and cleaning of one spark arrester without leaving the smoke pipe unprotected and also for the purpose of insuring better catching of sparks, I provide a plurality of spark arresting screens or devices. An important feature consists in the arrangement of such plurality of spark arresters so that they may be readily removed, and while removing one for cleaning the adjacent spark catching device is in place, and thereupon when the first device which has been removed is cleaned and replaced the next adjacent device can be removed, cleaned and replaced, and so on. While I contemplate the use of a plurality of such spark arresting devices I find that it is feasible to use two only, this construction giving the safety factor above mentioned,—of always having one arrester in position while the other is being removed, cleaned, or repaired and replaced, and furthermore two such devices are sufficient to prevent any dangerous sparks getting by.

Referring to the drawings illustrating a preferred form of the invention,

Figure 1 is a diagrammatic view of the interior of a tent, stove and smokepipe;

Fig. 2 is an enlarged fragmentary side view of a portion of the smokepipe built in accordance with my invention;

Fig. 3 is a front view;

Fig. 4 is a fragmentary side view of the encircling sleeve;

Fig. 5 is a front view of the sleeve;

Fig. 6 is a plan view of the spark arresting device and cross section on the lines 6—6 of Fig. 2; and

Fig. 7 is an enlarged side view partly in cross section; on the line 7—7 of Fig. 2.

A typical tent is shown at 1, such as is usually employed by the U. S. Army, as well as for commercial and recreation uses. A sheet iron heater 2 is shown in position in the center of the tent and the smoke pipe 3 leads from the heater out through the apex of the tent. To one of the sections in the smokepipe 3 I apply a sleeve 4 having a plurality, preferably 2, of slots as indicated at 5 and 6, the sleeve having also a vertical notch or slot 7 and 8 opening into the slots 5 and 6 respectively (see Fig. 3) to receive the projecting handle 10 of the spark arrester. The pipe section 3 adjacent

the sleeve 4 is similarly provided with corresponding slots 11 and 12, each slot having a central depression or notch 13, 13, as clearly shown in Fig. 5, said depression being adapted to receive the stem 10 of the spark arrester. Opposite the slots 11 and 12 in the pipe 3 are lugs 14, 14, coöperating with the notch 13, and preferably at the same level, to hold the spark arrester, the 10 rim 15 of said spark arrester resting on the lugs 14, 14, and the stem 10 resting in the notch 13 in each of the slots. A light wire mesh 16 carried by the frame 15 constitutes the spark arresting portion of the device. 15 These lugs 14 may conveniently be stamped out of the adjacent side of the pipe 3, the sleeve 4 acting to cover these holes, as also said sleeve covers the slots 11 and 12 when in lowered or closed position as shown in 20 Figs. 2 and 3.

In operation a section of the pipe 3 is provided with the semicircumferential slots and lugs 14 adapted to receive and hold the spark arresters, which can be conveniently 25 slid therein when the sleeve 4 is raised so that the slots 5 and 6 in said sleeve will register with the slots 11 and 12 in the pipe section. The spark arresters may then be slid into or out of position and when in position 30 the sleeve 4 is dropped and the slots 7 and 8 engage the stems 10 of each spark arrester, hold the same locked in position, while also holding the sleeve 4 from rotative position. When thus lowered the sleeve 35 4 covers the slots and openings in the pipe 3 and therefore the draft through the pipe is not impaired. When it is desired to clean either or both of the spark arresters, as when the same become slightly clogged, the 40 sleeve 4 is simply raised until the slots register and first one spark arrester removed, tapped or hammered slightly in order to clean the same and then replaced before the second spark arrester is removed for similar cleaning. By having a plurality of 45 spark arresting devices, the smokepipe 3 is thus at all times protected from sparks escaping and burning up the tent or other

building. Furthermore, by having the pipe section within convenient reach within the 50 tent, the spark arresters may be cleaned at any time and instantly. The advantage of this arrangement will be evident, as the former objectionable necessity of climbing up on top of the tent to remove, clean and 55 replace the old style spark arrester was so objectionable as to render the same a seldom performed duty. The apparatus is economical, efficient and can be applied to any existing smokepipe by fitting the same 60 to a pipe section of suitable diameter. While my invention is not particularly limited to use with a tent stove, and while it may be applied to any sized smokepipe for 65 many uses, it is especially important for application to a wood burning stove where highly inflammable material, such as the tent, woodyard, or the like, is adjacent the chimney. It will also be appreciated that my invention is not specifically limited to 70 the smoke pipes for tents, but is of general application, and therefore, in the appended claims, I have defined the pipe or other conduit as a tubular member.

My invention is further described and defined in the form of claims as follows:

1. A tubular member, having radial slots therethrough, and ribs adjacent said slots to receive a plurality of removable disks, a sliding sleeve outside said tubular member 80 having means therein to cover and close the said slots, the sliding of said sleeve acting to open the slots to view and permit removal of said disks.

2. A tubular member, having radial slots 85 therethrough, and ribs adjacent said slots to receive removable disks, each disk having a wire mesh and constituting an arresting device, a sliding sleeve outside said tubular member having means therein to cover and 90 close the said slots, the sliding of said sleeve acting to open the slots to view and permit removal of said disks.

In testimony whereof I have signed my name to this specification.

CHARLES T. CAHILL.
